OF DAYTON, OHIO, A CORPORATION OF DELAWARE.

IGNITION APPARATUS.

Application filed March 24, 1928. Serial No. 264,304.

This invention relates to ignition apparatus for internal combustion engines and particularly to means for controlling the timing of the ignition spark in accordance with the pressure characteristic of the combustion of the fuel charge in the engine. In the type of ignition controlling apparatus to which the present invention is related, the timing of the ignition spark is varied in accordance 10 with the position of a displacement member such as a piston movable within a pressure chamber, such as a cylinder, and subjected to combustion pressure impulses which occur at predetermined successive intervals during 15 combustion and which are alternately against opposite ends of the displacement member. Consequently the position in which the displacement member is located relative to the displacement chamber is dependent upon the 20 differential between the successive combustion pressures which are applied alternately to opposite ends of the displacement member.

In devices of this sort the pressure chamber is in direct communication with the combustion chamber of the engine and is therefore subjected to considerable heat. It is one of the objects of the present invention to provide a combination ignition timer and controller of the type referred to, in which the 30 controller will reliably operate notwithstanding the temperature to which it may be subjected and particularly to provide for such lubrication of the controller as will withstand high temperature.

A further object of the invention is to 35 simplify the valve mechanism which controls the successive admission of pressure to opposite sides or ends of the displacement member.

Further objects and advantages of the 40 present invention will be apparent from the following description, reference being had to the accompanying drawing, wherein a preferred form of embodiment of the present invention is clearly shown.

In the drawing:

Fig. 1 is a longitudinal sectional view of an 45 ignition apparatus embodying the present invention, and Fig. 1^a is a fragmentary plan view of the ignition interrupter.

Fig. 2 is a sectional view on the line 2—2 of Fig. 1.

Fig. 3 is a sectional view on the line 3—3 of Fig. 2.

Fig. 4 is a sectional view on the line 4—4 of Fig. 3.

Fig. 5 is a pressure-time indicator diagram of a conventional four-stroke cycle internal combustion engine and illustrates the manner of controlling the displacement member of 60 the ignition timer controller in accordance with impulses occurring at predetermined successive intervals during the explosion of fuel charge in the combustion chamber of 65 the engine.

It is well known that the ignition timer is a periodic circuit closer which is operated by a shaft driven by the engine. The circuit closer operates to close the circuit which includes an induction coil and a source of current in order that the coil may be energized while the circuit is closed, and then operates to break the circuit of the ignition coil so that its energy may be suddenly dissipated to produce a sparking impulse which is transformed to high voltage through the aid of the secondary coil of the induction coil. If the time relation between the opening of the ignition primary circuit and the engine cycle of operations is varied, it is apparent that the 70 timing of the ignition spark will be varied. The variation between the engine cycle and the operation of the circuit interrupter may be effected in different ways. In the present invention in Fig. 1, I show means for 75 varying the angular relation between the ignition primary circuit and the engine cycle of operations is varied, it is apparent that the 80 timing of the ignition spark will be varied. The variation between the engine cycle and the operation of the circuit interrupter may be effected in different ways. In the present invention in Fig. 1, I show means for 85 varying the angular relation between the ignition primary circuit and the engine cycle of operations is varied, it is apparent that the 90 timing of the ignition spark will be varied. The variation between the engine cycle and the operation of the circuit interrupter may be effected in different ways. In the present invention in Fig. 1, I show means for 95 varying the angular relation between the ignition primary circuit and the engine cycle of operations is varied, it is apparent that the 100 timing of the ignition spark will be varied. The variation between the engine cycle and the operation of the circuit interrupter may be effected in different ways. In the present invention in Fig. 1, I show means for 105 varying the angular relation between the ignition primary circuit and the engine cycle of operations is varied, it is apparent that the 110 timing of the ignition spark will be varied.

Fig. 1 is a longitudinal sectional view of an ignition apparatus embodying the present invention, and Fig. 1^a is a fragmentary plan view of the ignition interrupter. Fig. 2 is a sectional view on the line 2—2 of Fig. 1. Fig. 3 is a sectional view on the line 3—3 of Fig. 2.

37. The cam 30 is attached to a short shaft 40 journalled in a bearing 41 and having its lower end received by a recess 42 in the tubular upper end 43 in the shaft 21. The tubular end 43 is provided with diametrically opposite oblique slots shown at 44 in Fig. 1. The slot 44 receives a cross pin 45 which extends also through a longitudinal notch 46 in the shaft 40. The cross pin 45 is supported at 10 its ends by a grooved collar 47, which is adapted to be shifted by bifurcated lever 48 attached by screws 49 to a controlled shaft 50 and having studs 48^a received by the collar 47.
15. The controller shaft 50 is journalled in a bearing 51 supported by the frame 24 and in a bearing 52 supported by a cover plate 53 which together with the cup 25 and the cover plate 54 cooperate with the frame 24 to provide chamber 55 which houses the lever 48 and mechanism which connects the driving shaft 20 with the cam shaft 40. The cover plate member 53 is integral with a tubular member 60 which provides a pressure or displacement chamber 61 within which a displacement member or piston 62 is slidable. The piston 62 is connected by piston rod 63 and an arm 64 with the controller shaft 50. The lower end of the arm 30 64 is provided with a slot 65 for receiving a pin attached to the piston rod 63. The upper end of the arm 64 is attached to the shaft 50 by a screw 66. A screw 67 attaches an indicator 68 to the shaft 50 for the purpose of indicating the degree of advance or retard according to the position of the pointer 68 with reference to certain indexed marks which may be placed upon the outside of the frame 24. The ends of the tubular member or cylinder 60 are closed by plugs 69. Pressure fluid is admitted to the pressure chamber 61 on opposite sides of the piston 62 through ducts 70 and 71 which communicate with ports 70^a and 71^a respectively provided in the bearing 21 which is non-rotatably supported by the frame 24. Parts of ducts 70 and 71 are provided by the frame 24 and part by the cover member 53. The side wall of the bearing 21 opposite the ducts 70^a and 71^a is provided with two small ducts 72 and 73 communicating with a recess 74 in the frame 24 which is connected by suitable coupling 75 and pipe 76 with the engine combustion chamber, or with one of the combustion chambers in case of a multi-cylinder engine. The shaft 20 operates as a valve for controlling the admission of pressure fluid from the ducts 72 and 73 to the ducts 70 and 71. For this purpose the shaft 20 is provided with transverse passages 77 and 78 adapted respectively to place the duct 73 in communication with the duct 71, or the duct 72 in communication with the duct 70.
65. All of the shaft bearings, with the exception of the ball bearing 41, namely the bearings 21 and 22 for the shaft 20 and the step bearing 80 therefor, the bearings 51 and 52 for the shaft 50 and the piston 62 are formed preferably of self-lubricating metal, that is to say metal that is a substance comprising a porous metallic structure which is saturated with lubricant. This is found desirable in order that the bearing surfaces will be properly lubricated although they may be subjected to relatively high temperature. The bearings 22 and 80 provide a self-lubricating seal for the rotary valve provided by the shaft 20. The frame 24 provides a stuffing box for receiving packing material held in place by a suitable packing gland 82 in order to minimize leakage around the shaft 20.
- Assuming that the direction of rotation of the cam 30 is normally clockwise, as viewed in Fig. 1^a, it is evident that clockwise rotation of the cam 30 relative to the shaft 20 will advance the timing of the spark. This relative angular movement between the cam 30 and the shaft 20 will be produced by clockwise rotation of the controller shaft 50, as viewed in Fig. 1, or counter-clockwise rotation of the lever 64, as viewed in Fig. 4. In other words, a spark will be advanced as the piston 62 is moved toward the right in the cylinder 60; and, vice versa, the spark will be retarded as the piston is moved toward the left in Fig. 4.
- Referring to the pressure time diagram shown in Fig. 5, the line X—X is the zero pressure line and distances measured horizontally represent the time of the engine cycle in degrees of crank shaft rotation. The vertical line Y—Y denotes the position of the engine piston at upper dead center of the engine crank shaft. The vertical line b—b represents the instant at which the duct 71 is placed in communication with the engine combustion chamber and the line c—d represents the instant at which communication between the combustion chamber and the duct 71 is discontinued. The vertical line e—f represents the instant at which the duct 70 is placed in communication with the combustion chamber and the line g—h represents the instant at which communication between the duct 70 and the combustion chamber ceases. The shaded area between the lines a—b and c—d represents the time during which the right hand side or end of the piston 62 is subjected to explosion pressure, and the shaded area between the lines e—f and g—h represents the time during which the left hand end of the piston 62 is subjected to explosion pressure. Satisfactory ignition control for certain engines will be provided if the time during which either end of the piston is subjected to explosion pressure corresponds to 19 degrees of crank shaft rotation, and if the time interval between successive openings of the passages 71

and 70 to communication with the combustion chamber is 60 degrees, or, in other words, if the passage 70 is placed in communication with the combustion chamber 41 5 degrees after communication between the passage 71 and the combustion chamber is discontinued. It has been found satisfactory to open the duct 71 three degrees before upper dead center.

10 In order to explain how the spark is retarded or advanced according to the pressure characteristics of combustion, let it be assumed that the full line pressure time curve in Fig. 5 is representative of the characteristic of combustion when the engine is developing full load and that the broken line curve is representative of combustion when the engine is developing only part load. When the engine is developing only part load 20 a greater degree of spark advance is permissible than when it is developed in full load. It will be apparent upon observing where the broken line curve crosses the shaded areas that the pressure transmitted through the duct 70 will be greater than that transmitted through the duct 71; hence the piston 62 will be moved toward the right in cylinder 60 in order to advance the timing of ignition. The full line pressure curve representing full load 30 explosion characteristics crosses the shaded area between the lines *a*—*b* and *c*—*d* at points representing pressures higher than those occurring when the engine is operating at part load as represented by the broken line pressure curve. It is apparent, therefore, that the right hand end of the piston 62 will be subjected to greater pressures than the left hand end; consequently the piston will be moved 35 toward the left in order to retard the spark.

40 From the foregoing description of the construction and mode of operation of the present invention, it is apparent that by a very simple and economical construction I have provided for the control of ignition timing in accordance with combustion pressure characteristics of the fuel charge in the combustion chamber of the engine. By utilizing the rotating drive shaft of the timer as a rotary 45 valve I am able to control the admission of pressure fluid to the pressure chamber of the ignition controller without the use of separate slide or poppet valves and separate engine operated cams or similar devices for controlling the movements of the valves.

50 55 While the form of embodiment of the present invention as herein disclosed, constitutes a preferred form, it is to be understood that other forms might be adopted, all coming within the scope of the claims which follow.

What is claimed is as follows:

1. An ignition timer and controller therefor comprising a circuit interrupter; an engine shaft for operating the interrupter; and means for varying the time relation between the engine cycle and the functioning of the interrupter and including a displacement member movable in a pressure chamber, and means including a rotary valve operated by the shaft, for alternately subjecting opposite ends of the displacement member to engine combustion pressure occurring at predetermined successive intervals during combustion. 60

2. An ignition timer and controller therefor comprising a circuit interrupter; a rotary cam for operating the interrupter; an engine driven shaft for operating the cam; and means for varying the angular relation of the shaft and cam and including a displacement member movable in a pressure chamber, and means including a rotary valve operated by the shaft, for alternately subjecting opposite ends of the displacement member to engine combustion pressure occurring at predetermined successive intervals during combustion. 75

3. An ignition timer and controller therefor comprising a circuit interrupter; an engine shaft for operating the interrupter; and means for varying the time relation between the engine cycle and the functioning of the interrupter, and including a displacement member movable in a pressure chamber and means for alternately subjecting opposite ends of the displacement member to engine combustion pressure occurring at predetermined successive intervals during combustion, 80 said last named means including a rotary valve provided by ports formed in a journal of said shaft and cooperating with fixed ports provided by a bearing for said shaft journal. 90

4. An ignition timer and controller therefor comprising a circuit interrupter; a rotary cam for operating the interrupter; an engine driven shaft for operating the cam; and means for varying the angular relation of the shaft and cam, and including a displacement member movable in a pressure chamber and means for alternately subjecting opposite ends of the displacement member to engine combustion pressures occurring at predetermined successive intervals during combustion, said last named means including a rotary valve provided by ports formed in a journal of said shaft and cooperating with fixed ports provided by a bearing for said shaft journal. 105

In testimony whereof I hereto affix my signature.

WILLIAM A. CRYST.
